OVEN DOOR

Etienne Challet, Paris, France, assignor of one-fourth to Entreprises Electriques Fribourgeoises, Fribourg, Switzerland, a company of Switzerland

Application March 29, 1937, Serial No. 133,712
In Switzerland April 6, 1936

2 Claims. (Cl. 126—198)

The doors of ordinary ovens and in particular those of the ovens of kitchen ranges, most usually open by swinging about a lower hinge. This method of opening, which is logical when it is desired to withdraw what is in the oven, is quite unsatisfactory if it is desired only to inspect the rate of heating or of cooking and to make the necessary corrections therein if required. Although mica windows give a visibility of the inside, such visibility is imperfect and they do not permit of the piece of meat being manipulated, basted with gravy, turned over etc. It is therefore necessary to open the oven door and there is consequently a considerable loss of heat due to the outlet of hot air and the inlet of cold air, even if the door is simply placed ajar, since the communication of the inside of the oven with the outer air not only takes place through the top of the doorway, but also through the sides.

The present invention has for its object to avoid this waste, by using a door which can not only open like an ordinary door by swinging, but can also slide by moving downwardly in its plane, so as to leave an opening at the top. It can remain in this position as long as desired; the width of the opening thus obtained can moreover be made as small as desired.

This operation is obtained by means of guide grooves wherein the hinge pin passes so that the door is guided when it only slides. On the other hand, four metal rods and a spring arranged to form an articulated parallelogram abut against the lower pin and against the upper edge of the door. A spring tends to bring the parallelogram back to its initial shape and it is suitably calculated so that the weight of the door is balanced, and the door remains ajar in the position in which it has been placed without continuing its sliding movement.

The accompanying drawing shows an oven door according to the invention in various positions.

In said drawing:

Figs. 1 and 2 show in front elevation and in section, a door in the closed position.

Figs. 3 and 4 show in front elevation and in section, the same door which has slid slightly.

Figs. 5 and 6 show in front elevation and in section, the same door which has slid further.

As seen in Figures 1 and 2, the oven door 1 which is suitably lagged, is of course hinged as usual about a pin 2, and said door can be swung to the position 3 (Figure 2 in chain dotted lines) to completely open the oven.

On the sides of the door are provided slots 4 through which the pin 2 passes so that the door can move downwards more or less by sliding in its plane. To slide the door, a downward pressure is exerted on the handle 6.

In the body of the door is lodged an articulated parallelogram 7, the top corner 8 of which abuts against the upper flange 9 of the door and the lower corner 10 against the pin 2. Suitable stops prevent said corners 8 and 10 from escaping sideways.

A spring 11 which is suitably calibrated, balances the weight of the door. The latter therefore remains in the position which has been given it, as for example that of Figures 3 and 4, 5 and 6.

In Figures 3 and 4, there is a small opening, as at 5 for ventilation purposes.

If it is desired to watch and manipulate the objects placed in the oven, the downward movement of the door will be continued by pressing 20 on the handle 6 and the opening will be greater, as seen at 12 (Figures 5 and 6) where the door is in its extreme position.

To close it again, it suffices to exert a slight upward pressure on the handle 6, since the spring 25 brings back the arms of the parallelogram and it suffices to overcome the frictional forces.

I claim:

1. An oven door comprising a frame provided with slots, a door plate having a hinge at its bottom end, a hinge pin, and resilient means to hold the door plate in equilibrium; the aforesaid elements being so constructed and arranged that the door plate may be either swung outwardly around the hinge pin, or slide downwardly in its plane without simultaneously swinging outwardly; said resilient means for holding the door plate in equilibrium enabling the door plate to remain in whatever position is given to it, whereby an opening of variable height may be provided at the top.

2. An oven door according to claim 1, having slots in which the hinge pin is adapted to slide, the resilient means comprising four metal rods and a spring arranged to form an articulated parallelogram in the body of the door, which abut against the lower pin and against the upper edge of the door, said spring means tending to bring the parallelogram back to its initial position and calculated to balance the weight of the door.

ETIENNE CHALLETT.
